COMBINED MOLD AND PERMANENT OUTSIDE SHELL FOR EXTERIOR LIGHTING FIXTURE

Roger N. Ervin, 9647 Leaside Drive,
Dallas, Tex. 75238

Filed July 19, 1973, Ser. No. 380,873

Term of patent 14 years

Int. Cl. D26—03

U.S. Cl. D48—31

FIG. 1.

FIG. 2.

FIG. 3.

FIG. 4.

FIG. 5.

FIG. 1 is a perspective view of a combined mold and permanent outside shell for exterior lighting fixture showing my new design;

FIG. 2, a front elevation view thereof;

FIG. 3, a view representative of both rear and side elevation views thereof;

FIG. 4, a top plan view; and

FIG. 5, a bottom plan view thereof.

I claim:

The ornamental design for a combined mold and permanent outside shell for exterior lighting fixture, substantially as shown.
